SCYTHE GRIP

August Erikson, Foster Center, R. I.

Application May 29, 1936, Serial No. 82,642

1 Claim. (Cl. 56—326.6)

This invention appertains to new and useful improvements in grips or handles for loop-type scythe snaths.

The principal object of the present invention is to provide a novel grip or handle for scythes which can be readily positioned in place without likelihood of the same becoming loose or self-adjusting itself on the snath.

Another important object of the invention is to provide a grip or handle of the character stated which can be readily adjusted to the proper position on the snath without difficulty.

These and various other important objects and advantages of the invention will become apparent to the reader of the following specification.

In the drawing:

Figure 1 represents a longitudinal sectional view through the handle and snath;

Figure 2 is a side elevational view of the handle and snath with the handle partly in section;

Figure 3 is an enlarged fragmentary detailed sectional view of one end of the handle;

Figure 4 is an end elevational view of the handle.

Referring to the drawing, wherein like numerals designate like parts, it can be seen that numeral 5 represents the snath and numeral 6 the handle which can be of wood or some other suitable material. One end of this handle 6 is reduced as at 7 and disposed into the collar 8. The collar 8 is also provided with a reduced portion 9 around which the band 10 is disposed. This band 10 is closed at one side excepting for the slot 11 and its closed side is provided with sharp corrugations 12 which bite into the snath 5. Numeral 13 represents the loop provided with the elongated shank 14, which shank is split for the major portion of its length, as denoted by

numeral 15. The butt end of the shank 14 is provided with threads 16 over which the threaded cap 17 is disposed and wood screws 18 are employed with this cap 17 for securing the same definitely in position on the handle 6.

The handle 6 is provided with a bore therethrough for receiving the shank 14 and the loop 13 is provided with inwardly extending teeth or spurs 19 for biting into the snath 5. Obviously, the wood screws 18 can be removed and the cap 17 tightened to draw the loop 13 snugly around the snath 5 so that the teeth 19 will bite into the same while the sharpened corrugations 12 on the band 10 will also bite into the snath.

While the foregoing specification sets forth the invention in specific terms, it is to be understood that numerous changes in the shape, size, and materials may be resorted to without departing from the spirit and scope of the invention as claimed hereinafter.

Having described the invention, what is claimed as new is:

A handle for a sickle snath comprising a handle structure provided with a longitudinal opening therethrough, a ferrule at one end of the handle provided with a reduced extension, a cap member slidably disposed over the reduced extension of the ferrule and provided with a diametrical slot therein, a snath encircling loop having a portion thereof disposed into the slot and provided with a shank for disposition through the longitudinal opening in the handle, securing means between the shank and the handle, said cap having its slotted side of arcuate shape to conform with the curvature of the snath, and rows of snath biting ribs on the slotted side of the cap.

AUGUST ERIKSON.
